UNITED STATES PATENT OFFICE.

HANS FLEISSNER, OF LEOBEN, AUSTRIA.

BENZENE SAFETY LAMP FOR INDICATING FIRE DAMP.

Application filed August 31, 1926, Serial No. 132,814, and in Germany September 12, 1925.

This invention relates to miners' safety lamps of the kind having means for measuring the methane or firedamp content of the air in the mine and particularly to lamps 5 in which the increase in the methane content of the air is detected by a corresponding increase in the size of the flame.

Miners' lamps of the kind referred to have been proposed having a wire arranged 10 vertically in the lamp so as to be capable of being made incandescent by the flame. It has also been proposed to superpose a plurality of loops of platinum wire directly over the wick of the lamp so as to be capable 15 of being heated to incandescence by the flame and glowing with a red hue, the height of which varies with the content of gas in the air of the mine. Such arrangements, however, are only capable of measuring the 20 height of the flame and the indications become uncertain when the lamp is held in an inclined position. Arrangements have also been proposed in which a plurality of superposed transverse wires are employed 25 but the wires in these arrangements only act as measuring devices, being arranged at a comparatively great distance from one another and at such a distance from the flame that they are not capable of being 30 rendered incandescent thereby. These arrangements also can only measure the height of the flame and in this case also any inclination of the lamp will at least render the indication uncertain.

35 The present invention has for its object to provide a miner's safety lamp for testing the air for fire-damp, which will more clearly and reliably indicate the methane content of the air and in which the inclination 40 of the lamp will have no influence on the indication. With this object in view, the invention consists in arranging a metallic strip vertically inside the lamp casting directly above the burner at the normal 45 height of the flame so as to be in a position where it will be impinged upon and heated by the flame on the height thereof increasing beyond the normal height owing to the presence of methane in the air to be tested, 50 so as to show an incandescent patch comprising the image of a horizontal band of the flame having a size proportional to the methane content of the air.

The invention is illustrated by way of 55 example in the accompanying drawing in which:

Figure 1 shows an elevation partly in section of one constructional form of the improved safety lamp,

Figure 2 shows a modified form of metallic strip and

Figure 3 shows a second modified form of strip arranged above the lamp burner.

In the construction shown in Figure 1, the safety lamp comprises a casing *d* provided 65 with apertures *f* for admitting air to the inside of the lamp casing. Inside the casing *d* is fitted a burner *c* and directly above the burner is arranged vertically a strip of sheet metal *b*, which is supported by a stirrup *a* so as to be capable of being impinged upon by the flame *h* when the latter increases in size owing to an increase in the methane content of the air. The shape and 70 size of the flame is shown for different mixtures of air and methane according to observations which have been made. Thus it will be seen that the area of the strip *b* which is impinged upon by the flame *h* increases with the percentage of methane in 75 the air. As the strip *b* is capable of being made incandescent, the presence of methane in the air will be indicated by an incandescent patch on the strip, the size of which increases with the size of the flame and consequently in proportion to the methane 80 content.

Instead of employing a continuous, sheet metal strip *b*, as shown in Figure 1, the strip may comprise a plurality of horizontal wires 90 spaced apart at a small distance from one another as shown in Figure 2, which when rendered incandescent by the burner flame will produce the effect of a luminous patch in the same manner as the continuous strip 95 shown in Figure 1. In Figure 2 the wires *b* are arranged horizontally, but it will be understood that the wires could be arranged vertically without in any way affecting the result produced.

100 Figure 3 shows an arrangement in which a number of wires are mounted on the stirrup *a* in groups crossing one another so as to form a wire gauze *i* of close mesh which when heated by the burner flame will show 105 a luminous patch or spot varying in size with the size of the flame and thus with the methane content of the air to be tested.

What I claim is:

110 1. A miner's safety lamp for testing air for the presence of fire damp or methane, comprising the combination with a lamp

casing and a burner in said casing, of a metallic strip mounted vertically inside the lamp casing directly above said burner, at the normal height of a flame from said 5 burner, so as to be capable of being impinged upon by the flame and heated to incandescence by the said flame, on the height thereof increasing beyond the normal height owing to the presence of methane in the air 10 to be tested, said strip when so heated being capable of showing an incandescent patch comprising an image of a horizontal band of the flame having a length proportional to the methane content of the air.

15 2. A miner's safety lamp as set forth in claim 1, having the metallic strip compris-

ing a plurality of wires spaced apart at a small distance from one another, so as to form a screen capable of showing a luminous image of the horizontal band of the flame. 20

3. A miner's safety lamp as set forth in claim 1, having the metallic strip comprising groups of wires spaced apart at a small distance from one another with the wires of the said groups crossing one another, so 25 as to form a wire gauze, capable of showing a luminous image of the horizontal band of the flame.

In testimony whereof I have signed my name to this specification.

HANS FLEISSNER.
